RAILWAY SIGNALING SYSTEM

Howard A. Thompson, Edgewood, Pa., assignor to
The Union Switch & Signal Company, Swiss-
vale, Pa., a corporation of Pennsylvania

Application December 7, 1940, Serial No. 369,004

8 Claims. (Cl. 246—34)

My invention relates to railway signaling apparatus and particularly to systems of the type employing alternating current and single element track relays in the track circuits thereof.

Signaling systems of this type must be so designed that if an insulated joint separating two track sections becomes defective, energy supplied to one section cannot feed across the defective joint and produce a false operation of the track relay for an adjoining section.

It has heretofore been suggested to prevent this objectionable feeding of energy from one track section to another by providing a "lock-out" circuit to discontinue the supply of coded energy if a joint is defective, or by providing special forms of insulated joints or track circuit connections.

It is an object of my invention to provide a signaling system of the type having track circuits employing alternating current and having single element track relays, the system being arranged to prevent response of the track relay of each section to energy feeding across a defective joint from another section.

A further object of my invention is to provide a system of the type described and in which the alternating current energy supplied to the various track sections is modified so that the impulses of energy of one relative polarity therein are of substantially larger value than those of the other relative polarity so that a track relay of the direct current type may be employed.

A further object of my invention is to provide a system of the type described and employing direct current track relays of a type which are responsive only to energy of one relative polarity and having the track circuits of adjoining sections arranged so that the track relays thereof respond to energy of opposite polarity to thereby prevent response of a relay to energy feeding over a defective joint from an adjacent section.

Another object of my invention is to provide a system of the type described employing in the track circuits thereof a modified form of alternating current energy which will operate track relays of the direct current type and which will also effect operation of the standard forms of inductive cab signal apparatus carried by locomotives traversing the track stretch.

A further object of my invention is to provide means for supplying modified alternating current energy of the type required for use in a system of the kind mentioned above.

Other objects of my invention and features

of novelty will be apparent from the following description taken in connection with the accompanying drawing.

I shall describe one form of signaling system embodying my invention, together with several modified forms of apparatus which I may employ in this system, and shall then point out the novel features thereof in claims.

In the drawing

10 Fig. 1 is a diagram showing a stretch of railway track equipped with the signaling system provided by this invention;

Fig. 2 is a diagram of a typical alternating current voltage curve;

15 Fig. 3 is a diagram of the voltage curve of the alternating current employed in the system provided by my invention; and

20 Figs. 4 to 7 are diagrams showing other means which may be employed to provide the modified alternating current energy employed in this system.

Similar reference characters refer to similar parts in each of the several views.

Referring to Fig. 1 of the drawing, there is 25 shown therein a stretch of railroad track having track rails 1 and 2 over which traffic normally moves in the direction indicated by the arrow, that is from left to right. The rails of the track stretch are divided by insulated joints into the customary track sections. Two complete sections designated 12T and 13T, together with portions of the adjoining sections 11T and 14T are shown.

Each track section has at the entrance end thereof a signal S for indicating the nature of traffic conditions in advance. As shown, these signals are of the color light type and each is provided with a red or stop lamp R, a yellow or caution lamp Y, and a green or clear lamp G. While the system is illustrated as employing signals of the color light type, it should be understood that any type of signal may be employed, and also that the invention is applicable to track stretches without wayside signals and having cab signals only.

The rails of each of the track sections form a part of a track circuit to which coded alternating current of a modified form, as herein-after explained, is continuously supplied. The 50 signaling system shown is of the three indication variety and makes use of energy coded at two code frequencies, namely 75 and 180 energy impulses a minute which are separated by periods of equal duration during which no energy is supplied. The coded energy is provided by code

transmitters CT which have contacts 75 and 180 which are continuously actuated by a motor or other means.

The alternating current energy employed in this system may be supplied from any suitable source, such as a commercial source of current, and may be distributed throughout the track stretch by a transmission line, not shown. If energy from a commercial source is not available, the alternating current may be generated locally by tuned reed alternators. In the drawing the terminals of the source of alternating current are designated BX and CX, and it will be assumed that this energy is of a suitable frequency, such as 60 cycles per second.

Each of the track sections has at the entrance end thereof a code following track relay TR which is of the direct current type and incorporates a permanent magnet which renders the relay responsive only to energy which is predominantly of one relative polarity and non-responsive to energy predominantly of the other relative polarity. A relay of the type which I may employ is shown in United States Patent No. 1,959,562, issued May 22, 1934, to Harry E. Ashworth.

Each of the track relays has associated therewith a decoding transformer DT and auxiliary relays H and J. A contact 20 of each track relay controls the supply of energy from a local source of direct current, not shown, to the primary winding of the associated decoding transformer, while a contact 21 of each track relay rectifies the energy supplied from one secondary winding of the associated transformer to the associated relay H so that the relay H is energized when and only when the track relay is responding to coded energy.

Each decoding transformer is also provided with another secondary winding from which energy is supplied to the relay J through a suitable resonant rectifier unit which is arranged to permit sufficient energy to be supplied to the relay J to pick up the relay contact only when the energy induced in the decoding transformer secondary winding is of the frequency present when the track relay is responding to energy of the 180 code frequency.

Each track section is supplied with coded alternating current energy through a track transformer TT, while the primary winding of a transformer MT is connected in series with the connection of one terminal of the secondary winding of the track transformer TT to one of the track rails. The secondary winding of each transformer MT is short circuited through a rectifier or asymmetric unit K.

On the flow of energy through the primary winding of a transformer MT energy is induced in the transformer secondary winding. During the half cycles in which the energy induced in the secondary winding of transformer MT is of one relative polarity the energy can flow freely through the rectifier K so that the transformer secondary winding is short circuited, thereby reducing the impedance of the transformer primary winding with the result that energy may flow freely through this winding from the track transformer TT to the track rails.

However, during the half cycles in which the energy induced in the secondary winding of transformer MT is of the other relative polarity, the rectifier K prevents short circuiting of the secondary winding of the transformer MT with the result that the impedance of the primary

winding of this transformer is relatively high and offers considerable resistance to the flow of energy from the track transformer TT to the track rails.

It will be seen, therefore, that the action of the transformers MT is to modify the alternating current energy supplied to the track rails so that the impulses of energy of one relative polarity are of substantially greater value than those of the other relative polarity. The effect of the transformer MT is clearly shown in Figs. 2 and 3 of the drawing.

Fig. 2 is a diagram showing a typical alternating current voltage curve. This is the type of energy which would be supplied to the track rails if the transformers MT were not employed.

Fig. 3 is a diagram showing the voltage of the energy supplied through the transformer MT. As shown in this diagram, the impulses of energy of one relative polarity are of substantially greater value than those of the other relative polarity. To bring out the difference in the value of the impulses of different polarities, there is shown in broken lines, under the curve for the impulses above the zero line, the value which these impulses would have if they were equal to the impulses below the zero line.

As the impulses of energy of one relative polarity substantially exceed in value those of the other relative polarity, the energy supplied to the track rails has a direct current component which is equal to the difference in the value of the impulses of different polarities. This direct current component is effective to operate a direct current code following relay, while it has been found that the modified alternating current energy will produce proper operation of inductive cab signal apparatus carried by locomotives traversing the track stretch. The details of construction and operation of the locomotive cab signal equipment are not a part of the invention. One form of equipment which may be employed on the locomotives is shown in United States Patent No. 1,986,679, issued January 1, 1935, to Lloyd V. Lewis.

The track relays TR are of a type which respond only to direct current of one relative polarity, and the equipment is arranged so that the direct current component of the modified alternating current supplied to the track rails of each section is of the proper polarity to operate the track relay for that section. The relative polarity of the direct current component of the energy supplied to each section is indicated in the drawing by the usual designations.

In order to prevent operation of a track relay by energy feeding over a defective joint the direct current component of the energy employed in adjoining track sections is of opposite relative polarities.

The equipment is shown in Fig. 1 of the drawing in the condition which it assumes when the track stretch is vacant. At this time coded alternating current energy of 180 code frequency is supplied to the primary winding of the track transformer 13TT over a circuit controlled by apparatus, not shown, associated with section 14T.

On the supply of energy to the transformer 13TT coded alternating current of a modified form is supplied through the transformer 13MT to the rails of section 13T and to the relay 13TR. As pointed out above, the direct current component of the alternating current energy is such that the track relay 13TR will respond to this

energy. Accordingly, during the "on" intervals in the code the contacts of the track relay 13TR are picked up, while they are released during the "off" intervals in the code. As a result of this code following operation of the track relay 13TR, energy is supplied through the decoding transformer 13DT to the relays 13H and 13J and the contacts of these relays are picked up and establish the circuit of the green lamp G of signal 13S. In addition, as contact 25 of relay 13H is picked up, the circuit of the 180 contact of code transmitter 13CT is established so that energy of this code frequency is supplied to the rails of section 12T. As a result, signal 12S displays its green or clear indication, while energy of the 180 code frequency is supplied to the rails of section 14T.

When a train moving in the normal direction of traffic, that is from left to right, enters section 12T, the track relay 12TR is shunted and energy is no longer supplied through the decoding transformer 12DT to the relays 12H and 12J and these relays release, thereby interrupting the circuit of the green lamp G and establishing the circuit of the red lamp R of signal 12S. In addition, on release of contact 25 of relay 12H the circuit of the 180 contact of code transmitter 12CT is interrupted and the circuit of the 75 contact is established so that the energy supplied to section 14T is changed from 180 to 75 code frequency.

Likewise, when the train enters section 13T, the signal 13S is caused to display its stop indication, while energy of 75 code frequency is supplied to the rails of section 12T. When the train vacates section 12T, the track relay 12TR responds to this energy and current is supplied through the decoding transformer 12DT to pick up the relay 12H, but insufficient energy is supplied through the resonant unit to pick up the relay 12J. Accordingly, the signal 12S displays its yellow or caution indication, while energy of 180 code frequency is supplied to section 14T.

Similarly, when the train vacates section 13T, energy of 75 code frequency feeds to the track relay 13TR and the signal 13S is conditioned to display its caution indication, while energy of 180 code frequency is supplied to section 12T so that the signal 12S displays its green indication. When the train vacates section 14T, signal 13S is also conditioned to display its green or clear indication.

On movement of a locomotive equipped with cab signal apparatus through the track stretch the cab signal equipment will respond in the usual manner to the coded alternating current supplied to the track rails of the various track sections to provide the proper cab signal aspect.

In the system provided by this invention direct current track relays responsive to energy of one polarity only are employed, while the track circuits are arranged so that the direct current component of the energy in adjoining track sections is of opposite relative polarity. Thus in section 12T track rail 1 is negative and track rail 2 is positive, while in section 13T track rail 1 is positive and track rail 2 is negative.

When a train is present in section 13T, the track relay 13TR should be shunted and should not respond to coded energy. If at this time the insulated joints 3 separating sections 12T and 13T should be defective so that energy from the transformer 12TT feeds to the track relay 13TR, the track relay would not respond to this energy as the energy is of the wrong polarity. Accordingly, the track relay 13TR would re-

main released, while the signal 13S would continue to display its red or stop indication.

Similarly, if the insulated joints separating any other two sections should be defective so that energy from one section feeds to the track relay of the other, the track relay will not respond to this energy and will not improperly condition a signal to display a proceed indication.

10 In the system shown in Fig. 1 of the drawing there is shown one means for providing the modified alternating current with a direct current component which is required in this system. This energy may be provided in other ways, and Figs. 4 to 7 show other means for providing this energy.

In the system shown in Fig. 1 of the drawing the transformer MT has its primary winding connected in series with the secondary winding of the track transformer. The modification shown in Fig. 4 is similar to that shown in Fig. 1 and employs a transformer NT having its primary winding connected in multiple with the secondary winding of the track transformer TT. The terminals of the secondary winding of the transformer NT are connected together through a resistance 26 and a rectifier K.

Accordingly, when impulses of energy of one relative polarity are induced in the secondary winding of transformer NT, current flows through the rectifier K and is dissipated by the resistance 26. At this time, therefore, a part of the energy supplied from the secondary winding of the track transformer TT is consumed by the transformer NT so that the value of the impulses of energy supplied to the track rails is less than they would be if the transformer NT were not present.

When impulses of energy of the opposite relative polarity are induced in the secondary winding of the transformer NT, they are prevented from flowing through the resistance 26 by the rectifier K. Accordingly, at this time the transformer NT takes little or no energy from the track transformer TT and the impulses of energy supplied to the track rails are of substantially the full value supplied from the track transformer TT.

As the modification shown in Fig. 4 operates to provide impulses of one polarity which are of substantially higher value than those of the other polarity, the alternating current supplied to the track rails has a direct current component which will operate a direct current code following track relay as explained in connection with Fig. 1.

In Fig. 5 there is shown another means for providing the modified alternating current employed in this system. In this modification one terminal of the secondary winding of the track transformer TT is connected to one of the track rails through a resistance 28, while this resistance is shunted by a circuit including a rectifier or asymmetric unit K.

When impulses of energy of one relative polarity are induced in the secondary winding of the track transformer, they are prevented from flowing through the rectifier K so that the energy supplied to the track rails is supplied through the resistance 28 and is diminished thereby.

When impulses of the other relative polarity are induced in the track transformer secondary winding, they may flow freely through the rectifier K to the track rails so that these impulses are not reduced in value by the resistance 28.

Accordingly, the impulses of energy of opposite polarities supplied to the track rails are of unequal value so that the track circuit energy has a direct current component and will operate a direct current code following track relay.

The modification shown in Fig. 6 is similar to that shown in Fig. 5 and has a resistance 30 connected across the terminals of the track transformer secondary winding, while a rectifier K is connected in series with the resistance. When impulses of energy of one relative polarity are induced in the track transformer secondary winding, this energy may flow freely through the resistance 30 and the rectifier K so that a portion of these impulses are absorbed by the resistance. When impulses of energy of the other relative polarity are induced in the transformer secondary winding, they are prevented from flowing through the resistance 30 by the rectifier K and these impulses are supplied undiminished to the track rails. This modification operates, therefore, to provide impulses of energy of opposite polarities which are of unequal value so that the alternating current supplied to the track rails has a direct current component.

The modification shown in Fig. 7 shows another means for providing the track circuit energy employed in this system. This modification employs a special track transformer having two secondary windings 31 and 32 each of which is connected with the track rails in series with a rectifier or asymmetric unit K. The rectifier associated with winding 31 is poled to permit the supply of energy of one relative polarity to the track rails, while the rectifier associated with winding 32 is poled to permit the supply of energy of the other relative polarity. The windings 31 and 32 are proportioned so that the winding 32 has a substantially larger number of turns than the winding 31, while the two windings are arranged so that energy of the same relative polarity is induced in each at the same time.

When energy of one relative polarity is induced in the track transformer secondary windings, energy is supplied from the winding 31 to the track rails, but not from the winding 32. Similarly, when energy of the opposite polarity is induced in the track transformer secondary windings, energy is supplied to the track rails from the winding 32, but not from the winding 31. As the winding 32 has a substantially larger number of turns than the winding 31, the impulses of energy supplied from the winding 32 to the track rails are of substantially higher value than those supplied from the winding 31. Accordingly, the impulses of energy of one polarity supplied to the track rails substantially exceed in value those of the other relative polarity and the track circuit energy has a direct current component so that it will operate a direct current track relay.

While the system provided by this invention has been illustrated and described in connection with a signaling system employing coded energy in the track circuits thereof, it is not restricted to use in such systems.

Although I have herein shown and described only one form of railway signaling system embodying my invention, together with several forms of apparatus which may be employed therein, it is understood that various changes and modifications may be made therein within the scope of the appended claims without departing from the spirit and scope of my invention.

Having thus described my invention, what I claim is:

1. In a railway signaling system for use in track stretches over which are operated vehicles carrying signaling apparatus responsive to the flow of alternating current in the track rails, in combination, a stretch of railroad track having a pair of track rails divided by insulated joints into a plurality of track sections, a direct current track relay for each section having a winding connected across the rails of the associated section, a track transformer for each section, and means for each section for supplying from the transformer for the said section to the rails of such section impulses of energy of alternate relative polarity, each such means including a unidirectional impedance element and being arranged so the energy supplied from the transformer to the rails of the associated section includes impulses of energy of both polarities of substantial magnitude and also being arranged so that the potential of the impulses of one relative polarity supplied to the rails of the associated section is substantially higher than that of the impulses of the other relative polarity, whereby the energy supplied to said track rails is alternating in character so as to operate signaling apparatus on vehicles traversing the track stretch and is predominantly of one relative polarity so as to operate the track relays.
2. In a railway signaling system, in combination, a stretch of railroad track having a pair of track rails divided by insulated joints into a forward and a rearward section, each section having a direct current track relay having a winding connected across the rails of the associated section adjacent the entrance end thereof, said track relays being of a type which are responsive to energy of one polarity only, the relay for the forward section being responsive to energy of normal polarity and the relay for the rearward section being responsive to energy of reverse polarity only, a track transformer for each section, and means for each section for supplying from the transformer for the said section to the section rails adjacent the exit end of the section impulses of energy of alternate relative polarity, each such means including a unidirectional impedance element and being arranged so the energy supplied from the transformer to the rails of the associated section includes impulses of energy of both polarities of substantial magnitude and also being arranged so that the potential of the impulses of one relative polarity supplied to the rails of the associated section is substantially higher than that of the impulses of the other relative polarity, whereby the energy supplied to the rails of each of said sections is predominantly of one relative polarity and is effective to operate a track relay, the means for supplying energy to the rails of the forward section being arranged so that the impulses of energy of normal relative polarity predominate, the means for supplying energy to the rails of the rearward section being arranged so that the impulses of energy of reverse relative polarity predominate, whereby the track relay for each section will respond to energy supplied thereto from the supply means for such section and whereby the track relay for the forward section will not respond to energy feeding thereto across defective insulated joints from the rails of said rearward section.
3. In a railway signaling system, in combination, a section of railway track having a pair of track rails, a direct current track relay having a winding connected across the section rails adjacent one end thereof, a track transformer located adjacent the other end of the section, means

for supplying alternating current energy to the primary winding of said track transformer, said track transformer having one terminal of its secondary winding connected to one track rail of said section and having its other terminal connected to the other track rail in series with the primary winding of a modifying transformer, and a circuit including in series therewith an asymmetric unit for short circuiting the secondary winding of said modifying transformer, whereby the impedance of the primary winding of said modifying transformer to flow of impulses of energy of one polarity is greater than to the flow of impulses of energy of the other relative polarity, whereby the energy supplied from the track transformer is predominantly of one relative polarity and is effective to operate said track relay.

4. In a railway signaling system, in combination, a section of railway track having a pair of track rails, a direct current track relay having a winding connected across the section rails adjacent one end thereof, a track transformer located adjacent the other end of the section, means for supplying alternating current energy to the track transformer primary winding, said track transformer secondary winding having one of its terminals connected to one track rail and the other of its terminals connected to the other track rail of said section, a resistance included in series with the connection from one terminal of the track transformer to one track rail, and a circuit including an asymmetric unit in series therewith and shunting said resistance, whereby impulses of energy of one relative polarity are supplied from the track transformer to the track rails through said shunt circuit while impulses of energy of the other relative polarity are supplied to the track rails through the resistance, whereby the energy supplied to the track rails is predominantly of one relative polarity and is effective to operate said track relay.

5. In a railway signaling system, in combination, a section of railway track having a pair of track rails, a direct current track relay having a winding connected across the section rails adjacent one end thereof, a track transformer located adjacent the other end of the section, means for supplying alternating current energy to the primary winding of said track transformer, said track transformer having a first and a second secondary winding, one of said secondary windings being connected across the section rails in series with an asymmetric unit poled to permit energy of normal polarity to be supplied to the track rails, the other of said secondary windings being connected across the section rails in series with an asymmetric unit poled to permit energy of reverse relative polarity to be supplied to the track rails, whereby impulses of energy of one relative polarity are supplied from one of said secondary windings to the track rails and impulses of energy of the other relative polarity are supplied from the other of said secondary windings to the track rails, the equipment being arranged so that the transformer secondary windings alternately supply impulses of energy to the track rails, one of said secondary windings having a substantially larger number of turns than the other of said secondary windings, whereby the energy supplied from one of these windings is of substantially higher value than that supplied from the other of said windings so that the en-

ergy supplied to the track rails is predominantly of one relative polarity and is effective to operate said track relay.

6. In a railway signaling system, in combination, a section of railway track, a direct current track relay having a winding connected across the rails of said section, said relay being of a type which is responsive to energy of one polarity only, a track transformer for said section, and means including a unidirectional impedance element for supplying from said transformer to the rails of said section alternating current in which impulses of energy of both polarities are present in substantial magnitude and in which the potential of the impulses of energy of said one relative polarity is substantially higher than that of the impulses of energy of the other relative polarity.

7. In a coded railway signaling system, in combination, a section of railway track, a direct current code following track relay having a winding connected across the rails of said section, said relay being of a type which is responsive to energy of one polarity only, a track transformer for said section, means including a unidirectional impedance element for supplying from said transformer to the rails of said section alternating current in which impulses of energy of both polarities are present in substantial magnitude and in which the potential of the impulses of energy of said one relative polarity is substantially higher than that of the impulses of energy of the other relative polarity, and a coding device having a contact controlling a circuit for supplying energy from a source of alternating current to the primary winding of said track transformer.

8. In a coded railway signaling system for use in track stretches over which are operated vehicles carrying signaling apparatus responsive to the flow of coded alternating current in the track rails, in combination, a stretch of railway track having a pair of track rails divided by insulated joints into a forward and a rearward section, each section having a direct current code following track relay having a winding connected across the rails of the associated section adjacent the entrance end thereof, said track relays each being of a type which is responsive to energy of one polarity only, the track relay for the forward section being responsive to energy of normal polarity only and the track relay for the rearward section being responsive to energy of reverse polarity only, means for supplying to the rails of the forward section coded energy which is predominantly of normal polarity, a track transformer for said rearward section, means including a unidirectional impedance element for supplying from said transformer to the rails of said rearward section alternating current in which impulses of energy of both polarities are present in substantial magnitude and in which the potential of the impulses of energy of reverse polarity is substantially higher than that of the impulses of energy of normal polarity, whereby the energy supplied to the rails of said section is effective to operate vehicle carried signaling apparatus and is also effective to operate the track relay for said section, and a coding device having a contact controlling a circuit for supplying energy from a source of alternating current to the primary winding of said track transformer.

HOWARD A. THOMPSON.
